UNITED STATES PATENT OFFICE.

JAMES MACMASTER, OF DALLAS, TEXAS, ASSIGNOR TO INTERNATIONAL CONSERVATORY OF MUSIC, OF DALLAS, TEXAS, A CORPORATION OF TEXAS.

DESIGN FOR A MUSIC-INDICATOR.

No. 37,854.

Specification for Design.

Patented Feb. 27, 1906.

Application filed December 5, 1905. Serial No. 290,488. Term of patent 14 years.

To all whom it may concern:

Be it known that I, JAMES MACMASTER, a citizen of the United States, residing at Dallas, in the county of Dallas and State of Texas, have invented a new, original, and ornamental Design for a Music-Indicator, of which the following is a specification.

Referring to the accompanying drawing, forming a part of this specification, the figure

is a view in elevation of a music-indicator, showing my new design.

I claim—

The ornamental design for a music-indicator, as shown.

JAMES MACMASTER.
